UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A BACK FOR HAND-MIRRORS OR SIMILAR ARTICLES.

SPECIFICATION forming part of Design No. 29,530, dated October 25, 1898.

Application filed September 26, 1898. Serial No. 691,959. Term of patent 7 years.

To all whom it may concern:

Be it known that I, WILLIAM C. CODMAN, of Providence, in the county of Providence and State of Rhode Island, have invented and produced a new and original Design for the Backs of Hand-Mirrors or Similar Articles, of which the following is a specification, reference being had to the accompanying drawings, forming part thereof.

Figure 1 is a view of the back of the circular mirror provided with a loop. Fig. 2 is a sectional view of part of the back on the line *c d* of Fig. 1.

The leading feature of my design consists in the circular wreath formed of a series of foliated scrolls interspersed with floral ornaments inclosing a central panel.

In the drawings, A indicates the back of a circular mirror; B, the loop generally used on hand-mirrors; 1, the rounded margin of the circular back, and 2 the central panel. From the junction of the loop or handle B with the circular back extend the foliated scrolls 3 3 and 4 4 in a curved direction parallel with the circular margin of the back. The bold foliated scrolls 5 5 overlie the stems of the foliated scrolls 3 3, forming the lower

half of the circular wreath. The bold foliated scrolls 6 6 extend from the scrolls 5 5, curving inwardly parallel with the margin of the mirror-back and abut on the central ornament 7. A series of minor scrolls extend in circular directions under the main scrolls 5 and 6, and floral buds and leaves are interspersed between the scrolls.

The loop or handle B is ornamented with foliated scrolls following the contour of the loop.

The ornamentations are raised above the surface of the back, as is indicated by the shading of Fig. 1 and the partial section shown in Fig. 2.

Having thus described my invention, what I claim as new, and desire to secure by Letters Patent, is—

The design for the back of a hand-mirror or similar article substantially as herein shown and described.

In witness whereof I have hereunto set my hand.

WILLIAM C. CODMAN.

Witnesses:

JOSEPH A. MILLER,
B. M. SIMMS.
